GOLF HOLE SIMULATING DEVICE

Anthony J. O'Malley, Montclair, N. J.

Application April 4, 1950, Serial No. 153,925

4 Claims. (Cl. 273—36)

1

This invention relates to a practice device for use by golfers; and the invention has reference, more particularly, to a device capable of use in the home or elsewhere in doors for the practicing of putting strokes or shots.

It has been observed that a perfect eighteen hole round of golf, par seventy-two, concedes two putts on each green. It would therefore appear that at least fifty per cent of the strokes required during the play are for putting shots. This being so, it is highly desirable that the golfer, and especially the novice or beginner, should seek to improve putting skill. That this is recognized is evidenced by the fact that practice greens are almost universally provided as a desirable facility in connection with both private and public golf courses. Such practice greens are provided with the usual countersunk cups so that, when practicing, the golfer must repeatedly stoop to retrieve sunk balls from the cup, with the result that the golfer quickly tires, and frequently soon stops practice with consequent loss of benefit thereof.

Having the above mentioned facts in view, it is an object of this invention to provide a novel golf putting practice device which can be used on a carpet or rug within the home or other indoor locality; which device is so constructed that although closely simulating the target appearance of a practical cup, yet is such that necessity for constant stooping or bending over to retrieve a played ball is avoided, while at the same time means is provided to prevent far reaching escape of the ball in the event of misdirected or fast shots; all to the end that long continued practice may be beneficially carried on with a minimum of physical fatigue.

Another object of the invention is to provide a golf putting practice device which is so constructed that no surface impedance or obstruction is interposed in the path of the rolling ball toward and into the cup target; means being provided for admitting a properly directed ball moving at suitable velocity into the cup target, but allowing a ball shot at a velocity so high as to be likely to jump a practical cup to pass through and beyond the cup target with missed putt effect.

Other objects and advantages of this invention will become apparent as the following description is read in connection with the accompanying drawings, in which:

Fig. 1 is a top plan view of the golf putting practice device of this invention; Fig. 2 is a front elevational view of the same; Fig. 3 is a horizontal sectional view of the same, taken on line

2

3—3 in Fig. 2; and Fig. 4 is a transverse vertical sectional view thereof, taken on line 4—4 in Fig. 1.

Similar characters of reference are employed in the hereinabove described views, to indicate corresponding parts.

Referring to the drawings, the illustrative embodiment of the putting practice device according to this invention comprises a pair of spaced apart fore and aft extending foot members 10 upon which are supported side wall members 11, so as to bridge across and between the same is a top plate 12. This top plate 12 is provided with a central opening 13, which is centered medially between the side wall members 11. Disposed within said opening 13, in concentric relation thereto is a vertically movable brake ring 14 the walls of which are perpendicular to the plane of the top plate 12; said brake ring corresponding in diameter to the diameter of a practical green cup. Said brake ring 14 is yieldably supported from the top plate 12 by a pair of forward, radially disposed, suspension spring arms 15, and a pair of rearward, radially disposed, spring suspension arms 16; the walls of said brake ring 14 being perforated to permit the free ends of said spring arms to engage therethrough, whereby to suspend the brake ring within the top plate opening 13. The rearward end portions of the spring arms 15 and 16 are respectively affixed to the top plate 12 by fastening screws 17 which, preferably, pass downwardly through said top plate 12 to screw into the foot members 10, thus also assisting in binding the foot member, side wall members and top plate assembly together.

The brake ring 14 intersects the plane of the top plate, so that, as supported by the spring arms 15—16, the bottom edge 14' of the brake ring is normally disposed in a plane spaced above the level of the floor 18 upon which the device rests, and at a distance somewhat less than the diametrical size of a golf ball. A golf ball has a diametric size of $1\frac{1}{16}$ inches. The brake ring 14, as normally suspended by the spring arms 15—16, is so disposed that its bottom edge 14' is spaced from the floor level 18 at a distance of approximately $1\frac{1}{16}$ inches; the spacing thus being about $\frac{1}{8}$ inch less than the diameter of a golf ball.

Extending laterally outward in opposite directions from the forward or front ends of the respective side wall members 11 are stop wings 19 of suitable length. These stop wings 19 are preferably somewhat forwardly inclined toward their free ends, whereby, if struck by a misdirected putted ball, said ball will rebound there-

from toward the player, and thus will not escape from the vicinity of play, so that needless chasing of or searching for the ball is avoided. These stop wings 19 may be formed as an integral part of the side wall members 11 as shown, or may be separate parts suitably fixed in connection with the latter. Also provided in connection with the device is a back stop member 20. In a preferred form thereof, said back stop member is pivotally mounted by a knuckle 21 to turn about a forward fastening screw 17. The free end portion 20' of the back stop member 20 is turned to extend angularly inward relative to the main body thereof, so as to be disposed, in its operative position, in rearwardly spaced relation to and behind the rearward open end of the target cup assembly. When not in use, the back stop member 20 may be swung forward into alignment with the adjacent stop wing 19, whereby to reduce the bulk of the device for storage and for packing for transportation.

In the use of the putting practice device, the same is deposited on the carpet, rug or other suitable floor surface, and the user take stance a desired distance away from the front end thereof, placing a golf ball B on the floor ready to be addressed by a putting golf club, and thus ready to apply a putting stroke to said ball, endeavoring by the applied stroke to so direct the roll of the ball at proper velocity, considering the distance to be traversed by the ball to the target cup, that the ball will enter the open front of the device and come to rest within the target cup area. The power of the stroke must be so judged that the velocity of the putted ball will not be so great as would be likely to jump a practical cup if the shot were made on an actual green. If the velocity of the putted ball is properly determined, and its direction toward the target cup true, the ball will enter between the side wall members 11 of the device, and will engage the forward portion of the bottom edge 14' of the brake ring 14 with just sufficient force to cause said brake ring to upwardly yield, against the tension of the forward spring arms 15, to passage of the ball thereunder, the brake ring, under such conditions, exercising braking action upon the ball sufficient to assure its coming to rest within the target cup area. If, however, the power of the putting stroke is excessive, so that the velocity of the ball is great enough to be likely to jump a practical cup if the shot had been made on a golf course green, then not only will the ball pass the forward portion of the bottom edge 14' of the brake ring, but will also cross the target cup area, so as to engage and lift the rearward edge portion of the brake ring, with the result that the ball escapes the target cup area, with an effect similar to jumping a practical cup if the shot were made on a golf course green.

In order to properly control the brake ring for yielding to entrance of a putted ball into the target cup area when putted at suitable velocity, and also to yield to escape of a putted ball from the target cup area if the imparted velocity is such as to induce cup jumping, it has been found desirable to predetermine the tensile resistance of the front springs 15 at a selected tension, and the tensile resistance of the rear springs 16 at a somewhat greater tension. Ordinarily the tension of the front springs will be such that a ball moving at proper velocity will readily lift the forward edge por-

tions of the brake ring but will not lift the rearward edge portions thereof. It has been found that the tension of the rear springs 16 would be from two to four times greater than that of the front springs. Under these circumstances, a ball putted in proper direction and at proper velocity will pass under the forward portion of the brake ring, and in so doing its velocity will be so checked that it cannot lift the rearward portion of the brake ring, and consequently the ball remains in the target cup area, this being equivalent to sinking a ball if putted with like direction and force on a golf course green. On the other hand, a ball even though putted in proper direction, if at too high velocity, will, in passing the forward portion of the brake ring 14, not be sufficiently checked or slowed to be arrested by the rearward portion of the brake ring, but, on the contrary, will lift the latter so as to pass thereunder and thus jump or escape from the target cup area.

If desired the marginal area of the top plate which surrounds the opening and its contained brake ring may be colored in contrast to the remaining area of said top plate, whereby to visually define the mouth of the target cup area so as to assist the player in sighting the target cup area preparatory to a putting shot. If desired, the brake ring itself may be likewise colored to the same end.

It will be noted that the device, as deposited for use on a floor surface, is free from any floor surface obstructing parts in front of the target cup area, and consequently there is nothing to either impede or deflect the roll of ball as directed toward the target cup area by putting shot.

From the above, it will now be understood, that this invention provides a very simple, inexpensive and practical putting practice device for golfers, and one which is especially well adapted for home or other indoor use. Furthermore, not only does use of the device enable the user to attain desired skill in imparting proper direction to the putted ball, but also skill in judging required power of putting stroke best adapted to cover distance to the cup at a ball velocity which will not be excessive and thus risk jumping the cup.

Having now described my invention, I claim:

1. A putting practice device for golfers comprising a pair of laterally spaced apart upstanding side wall structures for deposit upon a playing surface whereby to define a fore and aft extending through passage therebetween, a top plate affixed to and bridging between the tops of said wall structures, said top plate having an opening above said passage, an upwardly movable brake ring within said opening, said brake ring substantially corresponding in diameter to the diameter of a practical green cup whereby to define a target cup area simulating the latter, and resilient means affixed to and extending over the upper surface of the top plate for supporting the brake ring in a normal initial lowermost position wherein its bottom edge is spaced above the playing surface at a distance somewhat less than the diametrical size of a golf ball, said brake ring being adapted to yield upwardly upon the passing of a moving golf ball thereunder.

2. A putting practice device for golfers as defined in claim 1 including laterally projecting stop wings extending outwardly from the forward ends of the respective side wall structures relative to opposite sides of the through passage entrance, and a back stop member connected with one side wall in rearward extension therefrom.

and having an angular free end portion spaced rearwardly from and opposed to the through passage exit.

3. A putting practice device for golfers as defined in claim 1 wherein the resilient means for supporting the brake ring comprises a plurality of radial suspension spring arms affixed to said top plate with their free end portions supportingly engaged through the wall of the ring.

4. A putting practice device for golfers as defined in claim 1 wherein the resilient means for supporting the brake ring comprises a plurality of radial suspension spring arms affixed to said top plate with their free end portions supportingly engaged through the wall of the ring, said 15 spring arms including a pair of forward arms and

a pair of rearward arms, the rearward arms being of stronger tension than the forward arms.

ANTHONY J. O'MALLEY.
